United States Patent Office

Des. 220,684
Patented May 11, 1971

220,684

BUILDING STRUCTURE INCLUDING UNDER-WATER LIVING ACCOMMODATIONS

William S. Page, 12862 Sylvan St., Garden Grove, Calif. 92641, and Lauren W. Anderson, Newport Beach, Reid A. Kawai, Pasadena, and Paul B. Kraus, Sunset Beach, Calif., and George C. Oyama, Mount Clemens, Mich.; said Anderson, Kawai, Kraus, and Oyama assignors to said Page

Filed Jan. 21, 1970, Ser. No. 21,016

Term of patent 14 years

Int. Cl. D25—04

U.S. Cl. D13—1

FIG.1

FIG.2

FIG. 3

FIG. 1 is a perspective view of a building structure including underwater living accommodations showing our new design;

FIG. 2 is a front elevational view thereof, the rear and side elevational views being identical; and

FIG. 3 is a top plan view thereof.

We claim:

The ornamental design for a building structure including underwater living accommodations, substantially as shown and described.
